BOILER CLEANER

Norman L. Snow, New Canaan, Conn., and Frank Bowers and Curtis L. Howse, Detroit, Mich., assignors to Diamond Power Specialty Corporation, Detroit, Mich., a corporation of Michigan

Original application August 28, 1924, Serial No. 734,746. Divided and this application March 23, 1931, Serial No. 524,724

5 Claims. (Cl. 122—391)

This invention relates to boiler cleaners and has particular reference to a boiler cleaner of the character in which a blower element is adapted to direct cleaning fluid adjacent portions 5 of the boiler to be cleaned.

One of the primary objects of the invention is to provide a blower mounted for rotative movement and to provide a fluid pressure actuated means for effecting a rotative movement of this 10 blower.

This application is a division of our copending application, Serial No. 734,746, filed August 28, 1924.

Other objects and advantages of the invention will become more apparent as the following description proceeds, particularly when reference is had to the accompanying drawings, wherein:

Fig. 1 is a top plan view partly in section showing the blowers applied to a locomotive boiler;

Fig. 2 is a side elevation thereof;

Fig. 3 is a sectional view showing a blower in inoperative retracted position;

Fig. 3^a is a detail sectional view along 3^a—3^a of Fig. 3;

Fig. 4 is a view along the line 4—4 of Fig. 3;

Fig. 5 is a view corresponding to Fig. 3 showing the blower in projected operative position;

Fig. 6 is a plan view of a device for automatically actuating a blower;

Fig. 7 is a sectional elevation along the line 7—7 of Fig. 6;

Fig. 8 is a sectional elevation along the line 8—8 of Fig. 6;

Fig. 9 is an end elevation partly in section of the device shown in Fig. 6;

Fig. 10 is a fragmentary side elevation of the device shown in Fig. 6; and

Fig. 11 is a section through the speed regulating cylinder of the device shown in Fig. 6.

Referring to Fig. 1 of the drawings, 10 indicates a locomotive boiler having the cab 11, boiler tubes 12 and boiler tube sheet 13. For cleaning these tubes there are located at the sides of the boiler, preferably extending through the water legs 14, a pair of blowers 15. These blowers are located a suitable distance from the tube sheet 13 with their nozzles 16 directed toward the tube sheet. Each blower has a connection with a steam supply by a pipe 17, the steam supply being controlled by valves 18 conveniently located preferably in the cab. The operating rods 19 are formed with suitable handle portions 20 and are operably connected with the blowers as herein-after set forth.

Referring to Fig. 3, rock arm 21 is adapted to be reciprocated with the pivot shaft 22 by the operating rod 19 and handle 20. While the arm is shown as manually operable it is obvious that the same may be automatically operated. The forward end of shaft 22 carries the pinion 23 keyed to the shaft and meshing with the broad face gear 24 carried within the housing 25. The housing 25 is provided with a forward part 26 which is fixed within the sleeve 27 in the water leg 14. The housing also has a wall 28 providing a bearing for the hollow rod 29, the rear end of which carries the gear 24. The forward end of rod 29 carries the blower head 30 on which is mounted the nozzle 31 formed with bevel gear 32. Bevel gear 33 meshes with the gear 32 and is carried by shaft 34 housed within and frictionally carried by rod 29. The rear end of the shaft 34 has keyed thereto the pawl wheel 35 engaged by the pawl 36 pivotally mounted on the face of the gear 24. The shaft 34 frictionally carries the segment 37 upon which is mounted the pawl 38 also engaging the wheel 35. The housing 25 is provided with the slot 39 and in the slot the heads of the set screws 40 and 40' are adapted to operate. The set screws may be located in any of the openings 41 in the segment 37 so as to limit the movement of the latter and vary the increment of advance of the blower nozzle as will be later apparent.

The spring 42 bears at its forward end against the stationary wall 28 and at its rear end acts upon spacing sleeve 43 and thrust bearing 44 to normally retract the parts to the position shown in Fig. 3. Between the part 26 and sleeve 27 air passages 27' are provided to afford air circulation to cool the blower.

The blower head 30, shown in Figs. 3 and 5, is provided at the forward end with a protecting heat-resisting cap 45 which is removably fastened to the blower head by pins 45^a. This cap may be formed of any one or combination of a number of different heat-resisting materials, examples of which are chromium iron alloy and nickel chromium iron alloy. When the blower is not in use this cap practically seals the end of water leg sleeve 27. The blower head is also provided with steam ports 46 between radial arms 46', as best shown in Fig. 3^a, and relief ports 47 in arms 46', the latter ports communicating with a passage 48, ports 49 and chamber 50. Plunger 51 is carried by the blower head 30. Passages 47^a are fitted with pet cocks 47^b for draining the blower body of condensate.

With the parts in position shown in Fig. 3, the

operation is as follows: Steam is admitted through the pipe 17 to the chamber 52 around plunger 51 to chamber 53, through ports 46 to the nozzle 31. The nozzle and ports restrict the flow of the steam so that the steam pressure will force the blower head outwardly, carrying the parts to the position indicated in Fig. 5. In this position the spacing sleeve contacts with the wall 28 to limit the outward movement of the parts.

10 The outward movement of the blower head 30 carries with it rod 29 and shaft 34 with the wheel 35, pawls 36 and 38, segment 37 and gear 24.

15 Steam escaping past the rod 29 and into chamber 50 will pass through ports 49, passage 48 and outlet ports 47.

With the parts of the blower in the projected position, the rock arm 21 is reciprocated to oscillate pinion 23 and gear 24. When the rod is moved to rock the gear 24 to the left or counter-clockwise as shown in Fig. 4, pawl 36 will rotate wheel 35. During this rotation the segment 37 which is frictionally carried on the shaft 34 also swings counter-clockwise until set screw 40 contacts with the wall of the slot 39 adjacent thereto.

20 25 Throughout the remaining stroke of the rock arm 21, pawl 38 permits the rotation of rod 34 and wheel 35 by the pawl 36. Thus, it will be noted that the blower head has been rocked with the nozzle without relative movement therebetween, the nozzle 31 directing its jet of steam for the vertical height of the tube sheet.

When the rock arm 21 is operated to rotate the gear 24 in the opposite direction or clockwise, as shown in Fig. 4, said operation rotates blower head 30, shaft 34, segment 37 and wheel 35 all together until further rotation of the segment is prevented by reason of the set screw 40' contacting with the wall of the slot 39 adjacent thereto. For the remaining movement of the rock arm 21, the pawl 38 prevents further rotation of the wheel 35 and shaft 34 and the gear 24 rotates the rod 29. During this remaining movement, therefore, the rod 29 will be rotated with respect to the rod 34 to act through the bevel gears 32, 40 45 33 to change the direction of the nozzle 31. By locating the set screws 40, 40' in the various openings 41, the increment of advance of the nozzle may be varied. The parts are then in position for the next cycle which will include first tracing a vertical path by the blower jet on the tube sheet substantially parallel with the preceding and spaced therefrom a distance determined by the relative movement between the gears 32, 33.

50 55 As the steam jets of the pair of blowers continue to sweep the face of the tube sheet vertically, the change in direction of each nozzle directs the jet in horizontal increments across the tube sheet until it reaches the center where the continued revolving of the nozzle brings it back to its original position. The nozzle thus has the combined movements imparted by the oscillation of rod 29 and the substantially horizontal movement of the nozzle with respect to the tube sheet.

60 Referring to Fig. 6, means is provided for automatically oscillating a blower. The housing 25 (Fig. 3) is preferably adapted to be removed at 54 in order to accommodate the housing 55. The pinion 23 and rock arm 21 of the blower construction shown in Fig. 3 are also removed, the housing 55 being provided with cylinders 56 and 57. Steam enters valve box 58 from a steam chamber 59 of the soot blower, this chamber corresponding to chamber 52 of the soot blower shown in Fig. 3, through port 60, thence through ports 61, 62, 63 70 and 64, to act on the piston 65. In the position

of the piston shown in Fig. 7, port 66 is uncovered and steam is conducted from the right end of cylinder 57 through ports 66, 67 and 68 to the right end of a valve 69, forcing the valve to the left, thereby admitting steam through inlet ports 61', 62', 63' and 64' to the left end of piston 65 and opening ports 64, 63 and 62 to the exhaust ports 70 and 71, thus allowing the right end of the cylinder 57 to exhaust to the chamber 72. From this chamber an annular passage 72a 10 extends around piston 65 to conduct the exhaust into the housing 55 from which it may discharge by way of port 55a.

15 As the valve 69 is forced to the left, it acts on the V-shaped plunger 73 in the V-notches 74 and 75, pushing the plunger up against the compressive action of the spring 76 until the point of the plunger rides over the point 77 between the V-notches 74 and 75. As soon as this point is passed the compression of the spring 76 forces the plunger 20 downwardly against the inclined side of the V-notch 75 to carry the valve the rest of the stroke to the left, thus preventing a dead center. As the piston 65 moves to the right it uncovers port 78, exhausting the steam from the right end of the 25 valve 69 by way of ports 68 and 67, thence through port 78 and slot 79 milled in the piston 65. It will be noted that slot 79 is in constant communication with chamber 72 and that the steam may therefore pass from slot 79 to chamber 30 72 and from this chamber by way of passage 72a to the casing 55. Port 78' is also uncovered by slot 79 until the piston reaches almost the extreme right position, so that any steam leaking around valve 69 will be exhausted. As the piston 35 65 nears the end of the right stroke, port 78' is covered and port 66' opened to exhaust the steam in the left end of the cylinder, the steam passing through ports 66', 67', and 68' to act on the valve 69 to force it to the right, thus reversing the 40 piston 65.

45 A portion of the bottom of piston 65 is provided with teeth 80 which engage the teeth 81 of the gear 24'. The gear 24' is operatively connected with a blower head and nozzle in the same manner as the gear 24 of Figs. 3, 4 and 5, the piston 65 automatically oscillating the gear 24' in a manner corresponding to the action of the pinion 23 and lever 21 of Fig. 4.

50 55 There are also provided teeth 82 in the side of piston 65 at right angles to the teeth 80. The teeth 82 engage a spur gear 83 which is rotatably mounted on the bearing 84. The gear 83 engages teeth 85 cut in the side of piston 86 within the cylinder 56 so that motion of the piston 65 in one direction moves the piston 86 in the opposite direction. The cylinder 56 is filled with oil which flows from one end of the cylinder to the other by reason of the port 87. The rate of flow is regulated by the valve screw 88 thereby determining 60 the speed at which the blower is operated.

65 In operation the valve 69 automatically controls the reciprocations of the piston 65 which actuates the gear 24' to clean the boiler tubes in a manner corresponding to that shown in Figs. 65 3, 4 and 5. Piston 86 serves to check the speed of operation of piston 65, the valve screw 88 being adjusted to obtain the desired speed.

70 75 From the above it will be noted that the invention provides a blower which is mounted for reciprocation and also for rotative movement. The arrangement is such that when cleaning fluid is supplied to the blower, the latter is projected to its blowing position and is oscillated by the piston 65 and associated structure. Thus the 75

invention provides means actuated by the pressure of the cleaning fluid for imparting a rotative movement to the blower element in addition to means actuated by the pressure of the cleaning fluid for effecting a projection of the blower to its operative position.

For the sake of convenience the invention has been described as being incorporated in a device for cleaning boilers. It will be apparent, however, that the inventive principles disclosed may be incorporated in devices for cleaning apparatuses similar to boilers, and it is to be therefore understood that the term "boiler" wherever used throughout the specification and claims is to be construed as meaning a fluid heater or heat transfer apparatus of any character, while the term "boiler cleaner" is to be construed as meaning a cleaner for any such apparatus.

While two embodiments of the invention have been described with some detail, it is to be understood that the description is for the purposes of illustration only and that the right is reserved to make such changes in the details of construction and arrangement of parts as will fall within the purview of the attached claims.

What we claim as our invention is:

1. In a soot blower, the combination with a casing, of a pipe reciprocative and oscillative in the casing, a nozzle on an end of the pipe projecting beyond the casing, means for supplying pressure fluid to the pipe to be ejected by the nozzle, a prime mover for reciprocating the pipe, a second prime mover for oscillating the pipe to sweep back and forth the jet emitted from the nozzle, and means common to both prime movers for controlling the operation of the same.

2. In a soot blower, the combination with a casing, of a pipe reciprocative and oscillative in the casing, a nozzle on an end of the pipe projecting beyond the casing, means for supplying pressure fluid to the pipe to be ejected by the nozzle, a prime mover for reciprocating the pipe, a second prime mover including a reciprocative element, and mechanism for translating reciproca-

tive movement into oscillative movement connecting the reciprocative element with the pipe to impart oscillative movement to said pipe.

3. In a soot blower, the combination with a casing, of a pipe oscillative and reciprocative in the casing, a nozzle on an end of the pipe projecting beyond the casing, means for supplying pressure fluid to the pipe to be ejected from the nozzle, means including a prime mover and power transmitting mechanism for oscillating the pipe, a power driven motor for reciprocating the pipe in the casing to vary the projection of the nozzle with relation to the casing, and a common control for the prime mover and the motor.

4. In a soot blower, the combination with a casing, of a pipe reciprocative and rotative in the casing, a nozzle on an end of the pipe projecting beyond the casing, means for supplying pressure fluid to the pipe to be ejected by the nozzle, a power driven motor for reciprocating the pipe to vary the projection of the nozzle with relation to the casing, mechanism for oscillating the pipe to sweep the jet emitted from the nozzle, a second power driven motor for actuating the mechanism for oscillating the pipe, and means common to both motors for controlling the action of the same.

5. In a soot blower, the combination with a casing, of a pipe reciprocative and rotative in the casing, a nozzle on an end of the pipe projecting beyond the casing, means for supplying pressure fluid to the pipe to be ejected by the nozzle, a pressure fluid motor for reciprocating the pipe to vary the projection of the nozzle with relation to the casing, mechanism for oscillating the pipe to sweep the jet emitted from the nozzle, a second pressure fluid motor for actuating the mechanism for oscillating the pipe, pressure fluid supply pipes communicating with both motors, and a common control valve for the supply pipes of both motors.
